UNITED STATES PATENT OFFICE.

ROBERT RESTALRIG LOGAN, OF NEW YORK, N. Y.

RACE-TRACK APPLIANCE.

SPECIFICATION forming part of Letters Patent No. 755,148, dated March 22, 1904.

Application filed August 25, 1903. Serial No. 170,683. (No model.)

To all whom it may concern:

Be it known that I, ROBERT RESTALRIG LOGAN, a citizen of the United States, and a resident of the borough of Manhattan, city and county of New York, State of New York, have invented certain new and useful Improvements in Race-Track Appliances, of which the following is a specification.

This invention relates to mechanism for determining with greater accuracy than has heretofore been customary the speed of races and also to determine with unvarying accuracy the exact positions occupied by the contestants at the finish.

For the purpose of describing my invention I will refer throughout to the foot-race known as the "one-hundred-yards dash," which is typical of the subject-matter of my invention. The trials and finals in the one-hundred-yards dash are usually run on a track somewhat longer than one hundred yards and over a straight course. There are ordinarily four contestants. In order that these four contestants shall run an equal distance, four lanes are made down the track of equal width by the use of cord or string supported on standards placed at long intervals apart. The race is commenced by the firing of a pistol, and a timekeeper allows his stop-watch to commence indicating the seconds. As these stop-watches are made they measure only fifths of seconds, and as the time for running the race is usually about ten seconds each fifth of a second represents the distance of two yards. It thus appears that if a contestant runs the race in the official time of nine and three-fifths seconds and another contestant runs it in nine and five-tenths seconds both racers will be credited with the same official time, although the second has run a faster race than the first.

It is one of the objects of my invention to determine the time consumed in running races of this character, so that the difference of inches will be accurately measured and timed.

A second object of my invention consists in determining the position of racers at the finish. As races are now run there are four judges of the finish. One judge must determine only who breaks the cord, the second judge receives the duty of determining who

ran second, the third judge who ran third, and the fourth judge who ran fourth. It frequently happens that the contestants cross the finish-line so closely together that it is possible only to determine who finished the first. The first man breaking the string is a matter readily determinable; but if the second and third at the finish cross the line only a half inch apart it is almost impossible for the judges to come to a satisfactory decision. My invention is designed to make this matter absolutely indisputable.

Generally speaking, the underlying idea of my invention consists in providing a goal corresponding to the finish of the course, the said goal being adjustable, so that it may be used on any track, and instead of providing one tape, to be broken by the runner who finishes first, I provide individual tapes adapted to break an electric circuit for each contestant. The breaking or removal of such tapes ruptures the electric circuit and registers the exact time of the finish for each contestant, and consequently the order in which the line is crossed by each contestant. The time-clock which I employ is one that may readily be obtained and which registers hundredths of seconds or smaller units, as desired.

Figure 1 of my drawings is a front view of the goal, which I set up at the finish-line. Fig. 2 is a top view of the same, and Fig. 3 a side view thereof. Fig. 4 shows the electric circuits; Fig. 5, the starting device; Fig. 6, the mechanism for holding the tape; Fig. 7, a face view thereof; Fig. 8 a side view of the adjusting mechanism for the tape-holding device, and Fig. 9 the adjusting mechanism of the top of the goal.

In the drawings, *a* designates the two end posts of the goal, which is erected over the finish-line. This goal is shown to be adjustable sidewise by means of slots and screws *A*, adjustably connected to the top cross-bar *b* of the goal, in order to accommodate it to different widths of track. Three vertical posts *c* are adjustably connected to the top cross-bar of the goal *b*, so as to obtain equal widths for the various lanes in tracks of different widths. This adjustment is made by means of screws *C*. At the side of the posts *a* and at each side of the intermediate posts *c* is a clamp-switch

d, adapted to be adjusted vertically by means of the screws *D*, so as to be accommodated to the heights of the various runners, if desired. Between two of these clamps or sockets *d* is 5 stretched the tape *e*, which is made adjustable lengthwise, so that when the goal-posts are on a broad track or on a narrow track they will serve their purpose. These tapes *e* are electric conductors and are provided at each 10 end with a projection *f*, adapted to engage with the two conducting-sections of the clamp *d* on the post. The two conducting-sections of each clamp *d* are insulated from each other and are connected by suitable wires running 15 upward over the goal to the electric circuit, as shown in Fig. 4. This circuit consists of the two wires 1 and 2, running down the side of the field, say, one hundred yards in length, and one of these wires, 1, is shown in the dia- 20 gram, Fig. 4, to be connected with four branch circuits 3, 4, 5, and 6, passing, respectively, through the time-clocks 7, batteries 8, and thence through the respective terminals of the 25 respective goals and the tapes connecting such terminals.

Fig. 5 shows an illustrative view of a starting device, consisting of the usual switch *g*, connected with pistol *h*. As the switch *g* is depressed and the pistol is fired and the runners start down the track the current is closed 30 at *g*, Fig. 4, throughout the entire circuit. As soon as a runner has reached the finish-line of the course he runs against the tape *e*, which is easily disengaged from the clamp or 35 socket *d*. The current being thus interrupted at that particular point will stop the electric time-clock 7 of that particular circuit. As each successive runner breaks his tape his particular clock will indicate the exact time of his 40 running, and therefore also his exact position in the race.

Of course instead of four clocks one time-clock may be employed to register only the time of the fastest runner. A branch circuit 45 in series with the main circuit may readily be arranged in connection with the tapes and a printing mechanism of suitable construction in such a manner that the first tape broken will stop the clock and at the same time 50 through the branch circuit print its mark on a moving strip of paper. The main circuit being thus absolutely broken the remaining three tapes will operate only on the branch circuit by printing their respective marks on 55 the moving strip of paper. In this manner, as well as when four time-clocks are employed, the exact time of the fastest runner, as well as the position of the other runners in a race, will be accurately and indisputably 60 determined. Instead of using four batteries and four branch circuits I may use one battery in the main circuit; nor do I wish to be limited to the particular construction of the various parts of my device.

Having thus described my invention, what 65 I claim is—

1. In mechanism for race-tracks of the character described, the combination of a plurality of independent tapes at the finish-line, and an electric circuit constituted by a plurality 70 of branch circuits connected with the tapes, each tape when struck by a racer being adapted to interrupt the current only in the respective branch circuit.

2. In mechanism for race-tracks of the character described, an electric circuit constituted by a plurality of branch circuits, a goal over the finish-line, and a plurality of tapes on such goal adjustable vertically independently of each other, each of such tapes having electrical connection in a different branch of said 80 electric circuit.

3. In a race-timing device, the combination of a plurality of indicating devices for the several contestants, mechanism for starting 85 said indicating devices simultaneously, and individual finish devices for each of said indicating devices.

4. In a race-timing device, the combination of a plurality of indicating devices for the 90 several contestants, mechanism for starting said indicating devices simultaneously, and individual devices adapted to be actuated by each of the contestants at the finish and to control the respective indicating devices. 95

5. In a race-timing device, the combination of a plurality of electrically-controlled indicating devices, one for each of the contestants, a circuit-closer for starting all of said indicating devices simultaneously, and individual interrupters, each in circuit with one of said indicating devices and adapted to be actuated by the respective contestant at the finish. 100

6. In a race-timing device, the combination 105 with a plurality of electrically-actuated indicating devices, one for each contestant, a plurality of interrupters located at the finish, one for each contestant and adapted to be actuated by the contestants, a circuit having 110 branches or shunts, each containing one of said indicating devices and one of said interrupters, and a circuit-closer common to all of said branches or shunts.

7. In a race-timing device, the combination 115 of a plurality of indicating devices for the several contestants, mechanism for starting said indicating devices simultaneously and at the same time giving a starting-signal, and individual finish devices for each of said indicating devices. 120

In testimony whereof I have signed my name to this specification in the presence of two subscribing witnesses.
